LIQUID-SEALED LIFTER ROOF FOR FLUID STORAGE APPARATUS

John H. Wiggins, Chicago, Ill.

Application February 13, 1946, Serial No. 647,385

3 Claims. (Cl. 48—176)

1

This invention relates to fluid storage apparatus of the particular type, that comprises a tank or equivalent stationary container having a side wall, a "lifter" roof, or vertically-movable roof for said tank provided with a skirt, dip ring or side wall portion arranged in telescopic relationship with the tank side wall, and a liquid seal for said roof composed of a reservoir extending circumferentially around the tank side wall and containing a liquid sealing medium, in which the side wall portion of the roof is immersed.

One object of my present invention is to provide a fluid storage apparatus of the general type mentioned, which is of such design or construction, that it is commercially practicable or feasible to use fuel oil as the liquid sealing medium.

Another object is to provide a fluid storage apparatus of the particular type mentioned, in which the liquid sealing medium is effectively protected from the atmosphere.

Another object of my invention is to provide a fluid storage apparatus of the particular type mentioned, which is of such construction that the liquid sealing medium is prevented from evaporating into the atmosphere.

And still another object of my invention is to provide a fluid storage apparatus of the kind above mentioned, in which the reservoir that holds the liquid sealing medium is provided at its upper end with an efficient closure of inexpensive construction, which, in addition to reducing evaporation losses and preventing the liquid sealing medium from becoming a fire hazard, also prevents snow and substantial quantities of rain water from entering said reservoir. Other objects and desirable features of my invention will be hereinafter pointed out.

In liquid-sealed lifter roofs of conventional design, used for volatile petroleum products, the roof is provided adjacent its peripheral edge with a depending tubular weather shield that surrounds the reservoir for the sealing liquid and prevents rain from beating into said reservoir, but no means is provided for protecting the liquid sealing medium from the atmosphere, or for preventing air from entering the upper end of said reservoir and circulating in contact with that portion of the surface of the sealing medium which surrounds or is located outside of the depending side wall of the portion immersed in the liquid sealing medium. Consequently, if fuel oil or any non-volatile petroleum product is used to constitute the liquid-sealing medium of a storage apparatus filled with gasoline or other highly

2

volatile material, then by laws of absorption of vapors, it is possible for said non-volatile product to become saturated with the highly volatile fractions of the gasoline stored in the apparatus, 5 thereby converting the liquid-sealing medium (the fuel oil in the reservoir) into a substance that evaporates rapidly and which constitutes a dangerous fire hazard, due to the fact that it consists of a highly inflammable liquid over which 10 air currents are constantly circulating. In an oil storage tank having a diameter of approximately 80 ft. and provided with a lifter roof that is capable of rising and falling a distance of approximately 10 ft., it is necessary to use nearly 15 3,000 gallons of fuel oil for the seal, whose cost after installation is in excess of approximately \$1,200.00. There is considerable gasoline loss, caused by absorption of gasoline vapors at the 20 surface of the fuel oil seal and gasoline condensation on the inner side of the depending side wall portion of the roof that runs down said side wall portion and mixes with the fuel oil in the reservoir, such gasoline condensation on the inner surface of the side wall portion of the roof tending 25 to cause the fuel oil seal to become supersaturated with gasoline. Moreover, the fuel oil seal always constitutes a fire hazard, inasmuch as the constant rise and fall of the lifter roof acts as a means to thoroughly mix the lighter and heavier fractions of the sealing oil, thus assuring that a mixture containing volatile fractions is exposed to the air side of the reservoir.

The apparatus herein described, which constitutes my invention, overcomes or eliminates the 30 above mentioned objectionable features or characteristics of liquid sealed lifter type tank roofs of conventional design, inasmuch as it comprises a closure for the reservoir which holds the liquid sealing medium, constructed and arranged so 35 that it protects the sealing liquid from the atmosphere, prevents snow and substantial quantities of rain water from entering the reservoir, and performs the above functions efficiently without interfering with or retarding the vertical 40 movement of the side wall portion of the roof during the rise and fall of the roof. In the preferred form of my invention herein illustrated, the above mentioned closure is formed by an 45 annular member made of gas-tight material, whose outer edge is attached to the outer wall of the sealing liquid reservoir, and whose inner edge is arranged in sliding engagement with the outer side of the depending side wall portion on the roof, the inner edge portion of said annular, 50 flexible closure being sustained by a supporting

means that presses said inner edge against the depending side wall portion on the roof.

Figure 1 of the drawings is a vertical transverse sectional view of a liquid-sealed, lifter type tank roof constructed in accordance with my invention.

Figure 2 is an enlarged fragmentary vertical sectional view through the reservoir that holds the liquid sealing medium, showing the normal position of the flexible closure at the upper end of said reservoir.

Figure 3 is a view similar to Figure 2, showing how the rockable carriers which support the inner edge portion of the closure are capable of moving radially so as to compensate for or provide for relative movement between the reservoir and the depending side wall portion on the roof; and

Figure 4 is a vertical sectional view, taken on approximately the line 4—4 of Figure 2, looking in the direction indicated by the arrows, so as to show the gaps or spaces between the horizontally-disposed, supporting bars on the rockable carriers and also to illustrate how said carriers can move circumferentially, to the right or to the left, to compensate for relative movement between the reservoir and the side wall portion of the roof, when either one of said parts goes out of round.

In the drawings, A designates the side wall portion of a tank that is adapted to be used for storing a fluid, usually gasoline or some other highly volatile material, B designates a lifter roof or vertically-movable roof for said tank, C designates a depending side wall portion, skirt or drip ring on said roof, arranged in telescopic relationship with the tank side wall, D designates an annular reservoir, herein illustrated as being attached to the side wall A of the tank adjacent the top edge of same and proportioned so that the annular outer wall of said reservoir will surround the side wall portion C of the roof, x designates a liquid sealing medium in the reservoir D, such, for example, as fuel oil, in which the side wall portion C of the roof is immersed, and E designates as an entirely a roof supporting structure inside of the tank, composed of a center post that supports a plurality of radially-disposed rafters whose outer ends are attached to the tank side wall A at the top edge of same.

The previously mentioned closure for the upper end of the sealing liquid reservoir D, preferably consists of a gas and liquid-tight, flexible member F, of annular form, whose outer edge or peripheral edge is attached by a clamping plate I to the top edge of the outer side wall of the reservoir D, and whose inner edge is maintained in sliding engagement with the outer surface of the depending side wall portion C of the roof. Preferably, the free edge or inner edge of the closure F is sustained by a supporting means that comprises a plurality of rockable carriers G, pivotally mounted on the inner side of the outer wall of the reservoir D in such a way that said carriers are capable of moving radially inwardly and outwardly to compensate for or provide for relative radial movement between the outer side wall of the reservoir and the depending side wall portion C of the roof, as shown in Figure 3, and are also capable of moving circumferentially a limited distance to the right and to the left, as indicated by broken lines in Figure 4, so as to provide for relative movement between the reservoir and the depending side wall portion C on the roof when either of said parts goes out of round. At the upper end of each of the carriers G there is a horizontally-disposed, arc-shaped

supporting bar 3 and a co-acting arc-shaped clamping bar 4, that support and grip the closure F at a point adjacent the inner edge of said closure, the clamping bars 4 being retained in position by nuts 5 on threaded studs or bolts 5^a that project upwardly from the supporting bars 3 and extend through holes in the closure F. The arc-shaped supporting bars 3 and their co-acting clamping bars 4 are not in abutting engagement with each other, but instead, the ends of the bars 3 and the ends of the bars 4 are separated by spaces usually of about one inch in length, as shown in Figure 4 of the drawings.

Due to the fact that the inner edge of the closure F is of considerably less diameter than the outer edge of said closure, I prefer to form the inner edge portion of the closure F from a relatively narrow, annular-shaped piece of gas-tight fabric F' that will lie substantially flat on the supporting bars 3 of the carriers G, and form the remainder of the closure F from a separate, annular-shaped, relatively wide piece of fabric that forms, in effect, a curtain-like closure that bridges the gap between the outer wall of the reservoir D and the inner edge portion F' of the closure that is in sliding engagement with the depending side wall portion C of the roof. The inner edge portion F' of the closure F constitutes a continuous, annular wiper of substantially fixed length, which, during the upward movement of the roof, will flex upwardly, and thus remain in snug wiping engagement with the side wall portion of the roof, and which, on the succeeding downward movement of the roof, will reverse or flex in the opposite direction. Said wiper F' can vary its length by stretching or compressing in the one inch gaps between the supporting bars 3 of the carriers G. However, said wiper F' has to change in circumference, but very little, since the side wall portion C of the roof is of the same circumference from its upper to its lower end. The wide, annular-shaped member, which constitutes the curtain-like, flexible portion of the closure F that bridges the gap between the wiper F' and the outer wall of the reservoir D, is of considerably greater diameter at its outer edge than at its inner edge. Consequently, when said part is being combined with the supporting and clamping bars of the carriers G, its inner edge must be folded or wrinkled sufficiently to make said inner edge of substantially the same diameter as the outer edge of the wiper F' when said parts are interposed between and clamped together by the bars 3 and 4 of the carriers G. Said wrinkles or folds are manually formed, and by pressure between the bars 3 and 4, are ironed out, so that a gas-tight connection is made between the relatively narrow, annular-shaped member, which constitutes the wiper F' of the closure F and the relatively wide, annular-shaped member which constitutes the remainder of the closure for the upper end of the reservoir D. At the gaps between the ends of the supporting bars 3 of the carriers, the two pieces of fabric that constitute the flexible closure F are cemented together, thus forming, in effect, a gas-tight closure that cuts off communication between the atmosphere and the space above that portion of the surface of the liquid sealing medium which surrounds or is located outside of the depending side wall portion C on the roof. Since the wiper F' is a substantially fixed length member, then in case the side wall portion C on the roof goes out of round, the wiper F' will slide circumferentially relatively to the side wall portion C of the

roof, due to the fact that the carriers D are pivotally mounted in such a way that, in addition to being capable of moving radially, inwardly and outwardly, they are also capable of rocking laterally a limited distance to the right and to the left, as indicated in dotted lines in Figure 4.

While I prefer to form the closure F for the reservoir D in the manner above described, due to the fact that such a closure is inexpensive to construct and easy to install, I wish it to be understood that my broad idea contemplates using any kind of a closure that will effectively cut off communication between the atmosphere and that portion of the surface of the liquid sealing medium which surrounds and is located outside of the depending side wall portion C on the roof, and at the same time provide for the rise and fall of the roof. As previously described, such a closure prevents snow from beating into the reservoir D, and it prevents substantial quantities of rain water from entering said reservoir. As a safety measure, the reservoir D can, if desired, be provided with a water discharge device for removing water from said reservoir, such, for example, as rain water that finds its way into the reservoir through the joint between the wiper F' and the side wall portion C of the roof, or water of condensation that collects on the inner surface of said side wall portion and precipitates through the liquid sealing medium x to the bottom of the reservoir D, the above-mentioned water discharged device being herein illustrated as an inverted syphon drain H attached to the bottom of the reservoir D, as shown in Figure 1.

Having thus described my invention, what I claim and desire to secure by Letters Patent is:

1. A fluid storage apparatus, comprising a tank adapted to hold a fluid that is being stored and provided with a stationary side wall, a vertically-movable roof for said tank provided with a depending skirt arranged in telescopic relationship with the tank side wall, a reservoir provided with an outer wall that extends circumferentially

- around the tank side wall said reservoir being adapted to contain a liquid sealing medium that is separate and distinct from the stored fluid in the tank, the depending skirt on the roof being immersed in the liquid sealing medium in said reservoir, a flexible closure at the upper end of the reservoir attached at its outer edge to the outer wall of the reservoir and having its inner edge portion arranged in sliding engagement with the outer surface of the depending skirt on the roof and radially-movable carriers mounted on the outer wall reservoir and attached to said flexible closure for supporting the inner edge portion of same that is arranged in sliding engagement with the depending skirt on the roof.
2. An apparatus of the kind described in claim 1, in which said carriers are attached to the reservoir by pivotal connections which have provision for permitting said carriers to move circumferentially a limited distance to the right and to the left, so as to provide for relative circumferential movement between the reservoir and the depending skirt on the roof when either of said parts goes out of round.
3. An apparatus of the kind described in claim 1, provided with means for automatically discharging from the lower end of said reservoir, rain water or water of condensation that has entered the upper end of the reservoir and precipitated through the liquid sealing medium in the reservoir.
